UNITED STATES PATENT OFFICE.

JOHN M. THOENNES AND CYRUS C. FISCHER, OF MILWAUKEE, WISCONSIN.

DESIGN FOR A RADIATOR CAP.

Application filed May 15, 1922. Serial No. 2,240. Term of patent 7 years.

To all whom it may concern:

Be it known that we, JOHN M. THOENNES and CYRUS C. FISCHER, citizens of the United States, residing at Milwaukee, in the county of Milwaukee and State of Wisconsin, have invented a new, original, and ornamental Design for Radiator Caps, of which the following is a description, reference being had to the accompanying drawing, forming part thereof.

In the drawing:

Fig. 1 is a side view and Fig. 2 is a top view of the radiator cap, showing our new design.

We claim:

The ornamental design for a radiator cap, as shown.

JOHN M. THOENNES.
CYRUS C. FISCHER.

Witnesses:
